(57) **CLAIM**

The ornamental design for a lumbar support, as shown and described.

DESCRIPTION

FIG. 1 is a front perspective view of a lumbar support.
FIG. 2 is a rear perspective view of the lumbar support of FIG. 1.

FIG. 3 is a front elevational view according to the lumbar support of FIG. 1.

FIG. 4 is a rear elevational view according to the lumbar support of FIG. 1.

FIG. 5 is a top plan view according to the lumbar support of FIG. 1.

FIG. 6 is a bottom plan view according to the lumbar support of FIG. 1.

FIG. 7 is a first side elevational view according to the lumbar support of FIG. 1; and,

FIG. 8 is a second side elevational view according to the lumbar support of FIG. 1.

The broken lines in the drawings are for the purpose of depicting portions of the lumbar support and hook and loop fastener, and form no part of the claim.

1 Claim, 5 Drawing Sheets
